Int. Cl. D6—01

U.S. Cl. D33—17

The characteristic features of my design reside in the surface patterns shown, in combination with the bow.

This application is a continuation-in-part of my co-pending application Ser. No. D. 8,630 filed Sept. 18, 1967 and now abandoned.

I claim:

The ornamental design for a toilet tissue roll cover, substantially as shown and described.
